US00D794009S

(12) **United States Design Patent** (10) Patent No.: **US D794,009 S**
Lee et al. (45) Date of Patent: ** Aug. 8, 2017

(54) **COVER FOR AN ELECTRONIC COMMUNICATIONS DEVICE**

- (71) Applicant: **Samsung Electronics Co., Ltd.**, Suwon-si (KR)
- (72) Inventors: **Ji Young Lee**, Seoul (KR); **Hong Gu Yeo**, Seongnam-si (KR); **Ji Hyun Ko**, Seoul (KR)
- (73) Assignee: **SAMSUNG ELECTRONICS CO., LTD.**, Suwon-si (KR)
- (**) Term: **15 Years**
- (21) Appl. No.: **29/588,397**
- (22) Filed: **Dec. 20, 2016**

Related U.S. Application Data

- (63) Continuation of application No. 29/522,191, filed on Mar. 27, 2015, now Pat. No. Des. 777,718.

(30) **Foreign Application Priority Data**

- Feb. 16, 2015 (KR) 30-2015-0008483
- (51) LOC (10) Cl. 14-03
- (52) U.S. Cl. USPC D14/250

(57) **CLAIM**

The ornamental design for a cover for an electronic communications device, as shown and described.

DESCRIPTION

FIG. 1 is a front perspective view of a cover for an electronic communications device showing our new design in a closed configuration;

FIG. 2 is a front view thereof;

FIG. 3 is a rear view thereof;

FIG. 4 is a left-side elevation view thereof;

FIG. 5 is a right-side elevation view thereof;

FIG. 6 is a top plan view thereof;

FIG. 7 is a bottom plan view thereof; and,

FIG. 8 is a front perspective view thereof showing our new design in an open configuration.

The dashed broken lines in the drawings illustrate portions of the cover that form no part of the claimed design.

1 Claim, 6 Drawing Sheets
